The ornamental design for a cane catcher, as shown and described.

DESCRIPTION

FIG. 1 is a front elevation view of the cane catcher of the present invention, the rear elevation view being a mirror image thereof;

FIG. 2 is a right side elevation view thereof; and,

FIG. 3 is a left side perspective view thereof showing the environment of the cane catcher in use.

The broken line showing of environment in the drawings is for illustrative purposes only and forms no part of the claimed design.
